COMBINED DOOR HANDLE AND LOCK HOUSING William J. Horgan, Jr., Allegheny County, Pa., assignor
to Blumcraft of Pittsburgh, Pittsburgh, Pa.Continuation-in-part of design applications Ser. No.
13,608, July 18, 1968, Ser. No. 19,456, Oct. 8,
1969, and Ser. No. 21,815, Mar. 9, 1970. This
application June 1, 1970, Ser. No. 23,211

Term of patent 14 years

Int. Cl. D8—06

U.S. Cl. D8—138

Fig. 9

Fig. 10

Fig. 11

FIG. 1 is a perspective view taken from the left front side of a combined door handle and lock housing embodying my new design;

FIG. 2 is an enlarged right side elevation taken as indicated by the lines and arrows 2—2 in FIG. 1, foreshortened in several places;

FIG. 3 is an enlarged foreshortened rear view of the embodiment shown in FIG. 1 taken as indicated by the lines and arrows 3—3 in FIG. 2;

FIG. 4 is a greatly enlarged top view taken as indicated by the lines and arrows 4—4 in FIG. 3;

FIG. 5 is a greatly enlarged section taken as indicated by the lines and arrows 5—5 in FIG. 3;

FIG. 6 is a perspective view taken from the left front side of another combined door handle and lock housing shown mounted on a door which is shown in phantom lines;

FIG. 7 is an enlarged foreshortened right side elevation taken as indicated by the lines and arrows 7—7 in FIG. 6;

FIG. 8 is an enlarged foreshortened rear view of the embodiment shown in FIG. 6 taken as indicated by the lines and arrows 8—8 in FIG. 7;

FIG. 9 is a greatly enlarged top view taken as indicated by the lines and arrows 9—9 in FIG. 8;

FIG. 10 is a greatly enlarged section taken as indicated by the lines and arrows 10—10 in FIG. 8;

FIG. 11 is a greatly enlarged section taken as indicated by the lines and arrows 11—11 in FIG. 8;

FIG. 12 is a perspective view taken from the left front side of another combined door handle and lock housing, shown mounted on a door which is shown in phantom lines;

FIG. 13 is an enlarged foreshortened right side eleva-

tion taken as indicated by the lines and arrows 13—13 in FIG. 12;

FIG. 14 is an enlarged foreshortened rear view of the embodiment shown in FIG. 12 taken as indicated by the lines and arrows 14—14 in FIG. 13;

FIG. 15 is a greatly enlarged top view taken as indicated by the lines and arrows 15—15 in FIG. 14; and

FIG. 16 is a greatly enlarged section taken as indicated by the lines and arrows 16—16 in FIG. 14.

The door shown in phantom lines forms no part of the design and has been included for purposes of illustrating environment only.

Portions have been foreshortened on the drawings for convenience of illustration.

The front views of the embodiments shown in FIGS. 1, 6 and 12 are identical to the rear views respectively of those embodiments as shown in FIGS. 3, 8 and 14 respectively.

This application incorporates by reference my prior copending applications Ser. No. D. 19,456, filed Oct. 8, 1969, Ser. No. D. 21,815, filed Mar. 9, 1970, and Ser. No. D. 13,608, filed July 18, 1968, and discloses and claims in part subject matter disclosed and claimed therein.

I claim:

The ornamental design for a combined door handle and lock housing, as shown and described.
